UNITED STATES PATENT OFFICE.

ALPHONS RAPPENECKER, OF BREMEN, GERMANY.

DEVELOPING APPARATUS FOR WRITING-TELEGRAPHS AND THE LIKE.

1,070,290.

Specification of Letters Patent. Patented Aug. 12, 1913.

Application filed July 8, 1912. Serial No. 708,283.

To all whom it may concern:

Be it known that I, ALPHONS RAPPENECKER, engineer, a subject of the German Emperor, residing at 102 Donanstrasse, 5 Bremen, Germany, have invented certain new and useful Improvements in Developing Apparatus for Writing-Telegraphs and the Like; and I do hereby declare the following to be a full, clear, and exact description of 10 the invention, such as will enable others skilled in the art to which it appertains to make and use the same.

This invention relates to an electrically driven developing apparatus for films, 15 chiefly for those writing-telegraphs which effect the transmission of communications by an electro-photographic process. The apparatus, however, can be used also for any other development apparatus. The working of the receiving apparatus of the first mentioned writing-telegraphs hitherto has not been completely automatic, as the receivers always had to be attended by some one who cut off, at a suitable point the exposed portion of the film which was to be developed, from the remaining stock of film. This was a drawback, for the receiving apparatus must be able to take text and pictures received and finish them photographically, even when nobody is present. To that end the device for cutting off the film is provided, according to this invention, with a gear which can be switched in or out from the transmitting station; the gear in question being preferably connected to the feed device for the film and of the construction hereinafter described.

Figure 1 shows diagrammatically the side elevation of the photographing and developing apparatus. Fig. 2 shows separately and 40 on an enlarged scale, the automatic shears used for cutting the film. Fig. 3 shows the corresponding connection diagram.

The upper portion of the camera *a* is occupied by the drum *b* with the film *c*, while in the bottom portion of the camera are arranged baths for developing and the like. The film *c* passes from the drum *b* first over the guide roller *d*, thence between the guide 50 rollers *e* and *e'*, in order to pass over the guide roller *f* where it turns and passes around the dipping roller *g* of the developing bath to the guide roller *h*, dipping roller *i* of the fixing bath and between the guide rollers 55 *k*, *k'* out of the casing. On the rollers situated in the interior of the casing are

mounted toothed wheels of about the same diameter arranged outside and marked with the same reference letters. The driving of the device is preferably effected from the electric motor *l* which, by means of the spindle *m*, rotates the worm wheel *n* connected by the toothed wheel *g* to the toothed wheels *f* and *h*. On the same spindle as the toothed wheel *g*, is mounted a smaller toothed wheel *o* for driving the spindle of the cam disk *q* on which is also mounted the toothed wheel *p*. The various rates of transmission and speed of rotation are calculated in such a manner that the cam disk *q* makes exactly one revolution during the complete operation of the device.

To the casing of the camera *a* is secured by means of bolts *r*, the lever *s* which slides by means of a block *t*, on the cam disk *q* 75 and is pressed against the latter by springs. The free end of the lever *s* is connected, preferably through a spring, to a slide *u* on which is mounted, free to rotate on a pin, the coupling wheel *v* which, on the slide being raised, couples the wheels *f* and *e'*. The slide *u* is adjustable in a guide of the casing *a* which can be closed so that no light can get in, and is controlled by a spring *w* which pulls it down (Fig. 2). The slide *u* 80 engages by means of an eye *x* a pin of the blade *y* of the shears, this blade being pivoted about a pin *z*. The other blade *y'* of the said shears is arranged in a fixed manner above the film. A spring *w'* engaging 85 with the pivoted blade *y*, tends to close the shears.

The working of the apparatus is as follows: As soon as the motor *l* has received current from the telegraphic transmitter 95 apparatus, it starts with the spindle *m* the worm wheel *n*, the toothed wheel *o* and the cam disk *q* (first a little idle movement). The worm wheel *n* drives also the toothed wheels *f* *h* and also *i* and *k*, *k'* but at first 100 without any action, as the film *c* and the rollers *e*, *e'* holding the same, remain unaffected. The coupling wheel *v* of the slide *u* is, at the moment, still at such a distance from the wheels *f* and *e'* that the teeth are 105 not yet in engagement. Only when the lever *s* is slowly raised by the cam disk *q* acting on the block *t* the slide *u* will also be raised and bring the coupling wheel *v* into engagement with the wheels *f* and *e'*. 110 At that moment the roller *e'* will pull the film and move it downward, so that as

much film as required by the telegram taken, will be carried under the fixed shearing blade y' to the baths. In the meantime, the cam disk q has made almost a complete revolution, the lever s has been raised still further, and turned the pivoted blade y of the shears, which was previously horizontal, into an almost vertical position. At the moment when the block t springs away from the cam of the cam disk q , the slide u springs back into the initial position into which it is pulled by the spring w (Fig. 2), the loose blade y of the shears springing then into the closed position of the shears and cutting the film e . On the cam disk q is mounted an electric contact device which, shortly before the end of the operative movement, breaks the circuit of the motor l , so that the gear stands still. The small additional movement of the motor (due to momentum) can be utilized for closing the contact again at the cam wheel q . At that moment, owing to special devices, the motor does not at once get current again, but remains standing still, until it again receives current from the transmitter station, which takes place only when a new section of film is ready for developing and cutting off. This is effected as follows: When at the transmitter station (Fig. 3), by a suitable operation of the writing pencil, or by any other means the contact 5 is closed within the line circuit 6 supplied with current by the source 7 , the relay 3 of the receiver station will attract the armatures 2 and thus close the circuit of the source of current 4 of the receiver station, which will thereupon drive the motor l . The motor starts the gear of the film and its cutting-off device, so that the cam disk q rotates. The spring contact l is normally closed and not affected by the cam disk q . Shortly before the end of its one revolution, a stop pin or the like of the cam disk q strikes a spring projection of the contact l and opens it for a moment, so that the relay 3 releases the armatures 2 and breaks the motor circuit. The motor continues, however, to rotate a little, so that the cam disk q completes its revolution, and the contact l , being released by the stop pin, is again closed. The motor l remains nevertheless without current, as the armatures 2 are lying free, and the line circuit is at rest. Obviously instead of the electric motor l a clockwork driving device could be employed released from the transmitter station.

What I claim is:—

1. A developing apparatus for writing telegraphs and the like, comprising motor-driven means for feeding a sensitized strip, means coöperating therewith for cutting off sections of said strip, in combination with means at the transmitting station for starting the motor of said feeding means.

2. A developing apparatus for writing telegraphs and the like, comprising motor-driven means for feeding a sensitized strip, means coöperating therewith for cutting off sections of said strip, means for stopping the motor after each cutting operation, in combination with means at the transmitting station for starting the motor. 70

3. A developing apparatus for writing telegraphs and the like, comprising a casing including a holder for a sensitized strip, motor-driven feed rollers for feeding the strip from the holder, cam controlled mechanism for coupling the initial feed rollers, and means associated with said cam control mechanism for cutting off sections of said strip, in combination with means at the transmitting station for starting the developing apparatus. 75

4. A developing apparatus for writing telegraphs and the like, comprising a casing including a holder for a sensitized strip, motor-driven feed rollers for feeding the strip from the holder, cam controlled mechanism for coupling the initial feed rollers, and means associated with said cam control mechanism for cutting off sections of said strip adjacent said initial feed rollers, in combination with means at the transmitting station for starting the developing apparatus. 80

5. A developing apparatus for writing telegraphs and the like, comprising a casing including a holder for a sensitized strip, a series of feed rollers for feeding the strip from the holder, motor-driven gearing for driving said feed rollers, an idler gear interposed in the gear train between the feed rollers, cam-operated means for engaging said idler gear in said gear train, and mechanism for severing the strip controlled by said cam-operated means, in combination with means at the transmitting station for starting the developing apparatus. 100

6. A developing apparatus for writing telegraphs and the like, comprising a casing including a holder for a sensitized strip, a series of feed rollers for feeding the strip from the holder, a gear train including an idler gear for driving said feed rollers, a cam driven from said gear train, a lever operated by said cam to engage the idler gear with said gear train, and a blade for severing the sensitized strip controlled by said lever, in combination with means at the transmitting station for starting the developing apparatus. 110

7. A developing apparatus for writing telegraphs and the like, comprising a casing including a holder for a sensitized strip, a series of feed rollers for feeding the strip from the holder, a gear train including an idler gear for driving said feed rollers, a motor for driving said gear train, a cam driven from said gear train, a lever op- 115 120 125 130

erated by said cam to engage the idler gear with said gear train, a blade for severing the sensitized strip controlled by said lever, and distantly controlled electrical means for 5 starting said motor.

8. A developing apparatus for writing telegraphs and the like, comprising a casing including a holder for a sensitized strip, a series of feed rollers for feeding the strip 10 from the holder, a gear train including an idler gear for driving said feed rollers, a motor for driving said gear train, a cam driven from said gear train, a lever operated by said cam to engage the idler gear with 15 said gear train, a blade for severing the sensitized strip controlled by said lever, an electric circuit controlled from a distance for starting the motor, and means operated by the gear train for breaking the electric 20 circuit after each severance of the strip.

9. A developing apparatus for writing telegraphs and the like, comprising means for feeding predetermined lengths of sensitized strip and means for severing the strip, a motor for actuating said feeding and cutting means, an electric circuit including a relay controlled from a distance for starting said motor, a second circuit including said relay to drive said motor, and a circuit breaker in said second circuit controlled by 25 the strip feeding means to interrupt the motor circuit after the severing means has operated.

In testimony whereof I have affixed my signature, in presence of two witnesses.
